UNITED STATES PATENT OFFICE.

WILLIAM S. HUNKINS, OF HOLLYWOOD, CALIFORNIA.

TAB END.

Application filed November 30, 1926. Serial No. 151,684.

This invention relates to "tab ends", so called, for garments, and consists in a novel form of pin tube so constructed and combined with a piece of fabric as to form a 5 complete "tab end", the end of the tab carrying the metallic tube being so formed that no metal is exposed for contact with the body or clothing of the wearer. The main object of the invention is to provide 10 an improved construction which will admit of very rapid and economical production of finished tab ends.

In the accompanying drawings

Fig. 1 is a relatively enlarged view of a 15 blank from which the pin tube is formed, the same being shown as applied to a strip of fabric preparatory to the final operation of rolling the blank into the form of a bushing or tube;

20 Fig. 2 is a side view of the tab end in its finished form;

Fig. 3 is a relatively enlarged end view 25 of the tab end shown in Fig. 2;

Fig. 4 is a section on the line 4—4 of Fig. 1;

30 Fig. 5 is a section on the line 5—5 of Fig. 3;

Fig. 6 is a view similar to Fig. 1 illustrating a modification of the pin tube blank;

35 Fig. 7 is a similar view showing another modification of the pin tube blank.

1 represents a plate of comparatively thin metal from which the pin tube proper is to be formed. The opposite ends of this plate

35 are slotted so as to form two tongue-like portions 1^a—1^a. 2 is the main body of a

piece of fabric, the side edges of which are turned in or folded as at 2^a—2^a. These

40 folds 2^a—2^a are respectively tucked under the tongues 1^a—1^a, as clearly seen in Fig. 1.

Downward pressure is then applied to each tongue so as to produce, in effect, a pinching or interlocking action between the plate

45 1 and the folds 2^a—2^a of the fabric, as best seen in Fig. 4. The plate 1 and the fabric

thus assembled are then bent into tubular form, so that the folded end of the tab will be equipped with an internal metallic bushing to receive and support a pin in the manner

50 characteristic of pin tubes in general. It will be observed that the rolling of the plate into tubular form brings the two free ends of the fabric strip together, so that

55 they may be conveniently applied to the garment to which the tab is to be attached.

In the modification shown in Fig. 4, 1

represents the rectangular plate, while 1^b—1^b represents the tongues of the ends of the plate. It will be observed that these tongues are formed by slitting the metal obliquely so as to give to the tongues a fish-tail formation. By reason of the shape of these tongues, when the same are interlocked with the folds 2^a—2^a of the fabric, a greater 60 resistance to slippage is offered.

65 In Fig. 7, I have shown another modification in which 1^c—1^c represent the tongues at the opposite ends of the plate 1. These tongues are formed with abrupt, right-angled shoulders 1^d—1^d as distinguished from 70 oblique shoulders as shown in Fig. 6. Here again the interlocking action is such as to offer very great resistance to slippage of either fold from the plate.

75 In the forms shown in Figs. 6 and 7, the plates are rolled up in the manner previously described to form an internal metallic bushing for each tab end, and, in both, the construction is such that the fabric may entirely cover the metal bushing, and thereby 80 protects the body and clothing of the wearer from contact therewith.

I claim:

1. In a tab end, a plate, a strip of fabric 85 covering the back of said plate with its edges folded around the side edges of said plate and extending partly over the top of the same, means for securing the folded edges of said fabric to said plate, said plate and fabric being rolled into tubular form to form 90 a finished tab end with a fabric covered metal bushing in one end thereof.

2. In a tab end, a plate, a strip of fabric covering the back of said plate and extending beyond the ends and edges of said plate, 95 the edges of said strip being folded around the side edges of said plate and partly over the front of the plate, said plate and fabric being rolled into tubular form to produce a finished tab end with a fabric covered metal 100 bushing in one end thereof.

3. In a tab end, a plate, holding devices at the opposite edges thereof, a strip of fabric covering the back of said plate with the edges of said fabric folded around the edges of the plate and partially over the front of the plate and engaged by said holding devices, said plate and fabric being rolled into tubular form to produce a finished tab end with a fabric covered metal bushing in one end 105 thereof.

110 4. In a tab end, a plate slotted at its side

- edges to form holding devices adjacent the side edges, a strip of fabric covering the back of the plate extending around the side edges of said plate and partially over the front of the plate and engaged by said holding devices, said plate and fabric being rolled into tubular form to produce a finished tab end with a fabric covered metal bushing in one end thereof.
- 10 5. In a tab end, a plate slitted to form two outwardly and oppositely directed holding tongues adjacent the side edges of said plate, a strip of fabric covering the back of the plate with the edges thereof folded around the side edges of the plate and extending partially over the front of the plate and under said tongues, said plate, tongues and fabric being rolled into tubular form to produce a finished tab end with a fabric covered metal bushing in one end thereof.
- 15 6. In a tab end, a plate slitted to form two outwardly and oppositely directed holding tongues adjacent the side edges of said plate, a strip of fabric covering the back of the plate with the edges thereof folded around
- 20
- 25

the side edges of the plate and extending partially over the front of the plate and under said tongues, said plate, tongues and fabric being rolled into tubular form to produce a finished tab end with a fabric covered metal bushing in one end thereof, the outer end of each of said tongues being of greater width than an inner part thereof for the purpose described.

7. In a tab end, a strip of fabric folded intermediate its length, a metallic bushing seated in the fold of said fabric strip, said bushing having an open slit in one side, the edges of said fabric extending into the ends of said bushing and through the slit therein.

8. In a tab end, a strip of fabric folded intermediate its length, a metallic bushing seated in the fold of said fabric strip, said bushing having an open slit in one side, the edges of said fabric extending into the ends of said bushing and through the slit therein, and means integral with said bushing to lock the edges of the fabric within the ends of said bushing.

WILLIAM S. HUNKINS.
